UNITED STATES PATENT OFFICE

2,523,601

ROCK CUTTING MACHINE

Edward Swift, Chula Vista, Calif.

Application June 5, 1947, Serial No. 752,612

9 Claims. (Cl. 125—23)

1

This invention relates to improvements in rock cutting machines.

An object of the invention is to provide an improved rock cutting machine which will employ vertically adjustable upper and lower disk-shaped cutters which will be hydraulically forced towards each other upon the upper and lower surfaces of a rock when clamped between upper and lower travelling tables reciprocably mounted for movement between said cutters.

Another object of the invention is to provide an improved rock cutting machine which will employ reciprocably mounted upper and lower rock supporting tables having means for clamping a rock therebetween, and a plurality of rows of upper and lower vertically adjustable disk-shaped rotary cutters adapted to engage the upper and lower surfaces of the rock to be cut, being operated by a series of hydraulically operated eccentric cams.

A further object of the invention is to provide an improved rock cutting machine including a main supporting frame upon which cooperating upper and lower rock supporting tables are reciprocably mounted with anti-slipping means being incorporated in the upper table, and disk-shape cutters supported by upper and lower cutter supporting beams disposed transversely of said tables and having hydraulically operated eccentric cams for moving said cutter supporting beams towards the rock supported between the tables until the cutters are forcibly engaged with the upper and lower surfaces of the rock as it and its supporting tables are moved between the cutter beams and cutters.

Another object of the invention is to provide an improved hydraulically operated rock cutting machine which will be highly efficient in operation, and relatively inexpensive to manufacture and produce.

Other objects will appear as the description proceeds.

In the accompanying drawings which form a part of this application,

Figure 1 is a side elevation of the improved hydraulically operated rock cutting machine;

Figure 2 is a plan view of the improved hydraulically operated rock cutting machine;

Figure 3 is an end view of the improved hydraulically operated rock cutting machine;

Figure 4 is a sectional view taken on the line 4—4 of Figure 2;

Figure 5 is a sectional view taken on the line 5—5 of Figure 2;

Figure 6 is a sectional view taken on line 6—6 of Figure 4;

Figure 7 is a detail sectional view taken on the line 7—7 of Figure 1;

Figure 8 is a detail side elevation of the bearing rollers for the lower rock supporting table

2

showing the same supported in rolling contact on the machine frame;

Figure 9 is a detail perspective view of the bearing rollers for the lower rock supporting table, also showing a side thrust roller bearing for the table edge;

Figure 10 is a detail perspective view of a pair of frame uprights with the upper and lower cutter supporting beams disposed thereon for vertical adjustment, and

Figure 11 is a perspective view of one of the disk-shape stone cutters with its yoke mounting support.

Like characters of reference are used throughout the following specification and the accompanying drawings to designate corresponding parts.

In carrying out the invention, there is provided a substantially rectangular supporting frame generally designated by the reference numeral 1, the same being formed of angle iron upper side members 2 and 3, and lower side members 4 and 5 connected together by means of the vertical standards 6 formed of similar angle iron construction. Upper end cross members 7 and 8 are connected between the opposite ends of the upper side frame members 2 and 3, while lower end cross members 9 and 10 are connected between the opposite ends of the lower side frame members 4 and 5. These angle iron frame members are preferably welded together to provide a rigid construction, while angular reinforcing web members or plates 11 are welded in the several corners of the frame.

A lower rock supporting table 12 is formed substantially rectangular in shape from a plurality of spaced parallel T-shape angle iron bars 13, the same being held in fixed position within the angle iron outer frame members 14.

Depending pairs of supporting rollers 15 are mounted upon the inverted Y-shape supports 16 at the front and rear of the lower supporting table 12 and at either side thereof, and are adapted to engage the upper flat surfaces of the side frame members 2 and 3 of the main frame 1 for reciprocating movement.

A transversely disposed shaft 16' is mounted adjacent the end of the frame 1 between the upper side frame members 2 and 3, supporting the arms 17 and 18 on their outer extremities, which in turn are secured to the pitman rods 19 and 20 secured at their opposite ends to the reciprocable lower rock supporting table 12.

Upwardly extending brackets 21 are secured to the upper side frame members 2 and 3, and support the side thrust roller bearings 22 which engage the sides of the lower stone supporting table 12 to steady and guide the same as it moves back and forth over the main frame 1.

A pair of upwardly extending arms 23 and 24

are secured to the ends of the upper cross frame member 8, and rotatably support the feed roller 25 mounted therebetween for supporting and guiding the rock (not shown) as it is fed onto the lower rock supporting table 12.

Pairs of upwardly extending oppositely disposed angle iron standards 26 and 27 are welded to the opposite ends at either side of the lower rock supporting table 12, and support the apertured ears 28 on their upper ends, in which the upper ends of the coil supporting springs 29 are supported. The lower ends of the coil springs 29 are secured to the upper rock clamping table 30, which is formed with a substantially rectangular frame 31 of angle iron, to which the spaced longitudinally extending inverted U-shaped channel members 32 are secured in spaced relation, preferably by welding. A length of rubber hose 33 is secured in each of the inverted U-shape channel members 32 and extend below the lower extremities thereof to engage the upper surface of a rock (not shown) when clamped between the lower supporting table 12 and the clamping table 30 to provide a non-slipping clamping engagement with the rock, the function of the coil springs being to resiliently hold the rock clamping frame 30 in spaced position above the rock supporting table 12 when the machine is not in actual operation.

A transversely extending shaft 34 is mounted between the bracket arms 35 and 36 secured to the standards 27, and supports the actuating cams 37 and 38 which bear upon the upper ends of the rock clamping frame 30. The toothed quadrants 39 and 40 are secured to the standards 27 and are adapted to be engaged by the dogs or pawls 41 and 42 pivotally mounted at 43 on the cams 37 and 38.

An operating lever 44 is secured centrally on the shaft 34 and terminates in the handle 45, and a connecting rod 46 is pivotally connected thereto, being connected at its opposite end to a turn-buckle 47, and a similar connecting rod 48 is connected between the turn-buckle 47 and the chink 49 attached at 50 to the cross shaft 53 upon which are mounted the actuating cams 51 and 52 bearing upon the inner end of the rock clamping frame 30, whereby operation of said handle 45 will simultaneously operate the oppositely disposed actuating cams 37 and 38, and 51 and 52 to lower and clamp the rock clamping table 30 in the desired clamped position.

Two vertically extending pairs of spaced elongated angle iron standards 54 and 55 are attached to the opposite side frame members 2 and 4, and 3 and 5, and support the upper and lower angle iron reciprocating guide bracket members 56 and 57, between which the upper and lower cutter supporting beams 58 and 59 are respectively supported.

Each of the cutter supporting beams 58 and 59 are formed of box construction with spaced parallel extending arms 60 and 61, between which the yokes 62 are secured by the bolts 63, and between which the axles 64 are mounted for supporting the ball bearing races 65 and superimposed disk-shaped cutters 66, said cutters being disposed in vertical alignment to extend through the slots 67 formed by the spaces between the spaced parallel extending T-shape angle iron bars 13 in the lower rock supporting table 12, and between the spaces formed by the spaced inverted U-shape channel members 32 in the rock clamping table 30.

The upper disk-shaped cutters 66 and thin

supporting beams 58 are provided at their opposite ends with the hooks 68 which are engaged by the chains 69 secured to the lower ends of the coil springs 70, whose upper ends are secured to the cross bolts or pins 71 disposed between the upper ends of the pairs of standards 54 and 55.

Secured to the reciprocating guide members 56 and 57 and vertically movable therewith, are the bracket members 72 and 73 respectively, between which the longitudinally extending shafts 74 and 75 are mounted.

Actuating cams 76 and 77 are fixed to the opposite ends of the shafts 74 and 75, and each of the cams 76 and 77 supports the ball bearing rollers 78 and 79 for rolling engagement with the flat terminal ends 80 and 81 of the disk-shape cutter supporting beams 58 and 59 for forcing the same together when actuated by the hydraulic cylinder 82 and its associated linkage now to be described.

Upwardly extending links 83 are pivotally supported upon the cross shafts 74, while the downwardly extending links 84 are pivotally supported upon the lower cross shafts 75.

The outer ends of the links 83 are connected together by the connecting rods 85 and 86, which are connected together at their adjacent ends by the turn-buckle 87. Similarly, the outer ends of the links 84 are connected together by the connecting rods 88 and 89 which are connected together at their adjacent ends by the turn-buckle 90.

The shafts 74 and 75 and their actuating cams 76 and 77 are mounted for vertical adjustment in the bracket plates 91 and 92 secured to the disk-shape cutter supporting beams 58 and 59, being held in the desired position by means of the securing or locking bolts 93.

The hydraulic cylinder 82 is supported at its lower end by the fixed arm 94, which in turn is connected by the link or arm 95 with the arm 84 and cam shaft 75.

The piston (not shown) in the cylinder 82 is connected to the piston rod 96 extending from the upper end thereof, and is connected by means of the link or arm 97 with the cam shaft lever 83 secured to the cam shaft 74.

Oil under pressure will be fed through the inlet tubing 98 to the upper part of the cylinder for actuating the piston when the disk-shape cutter supporting beams 58 and 59 are to be moved together to cut a rock (not shown). The tubing 98 is connected with the lower end of the cylinder 82 for releasing the pressure on the rock after it has been cut.

Pivoted pawls 100 will be mounted on the cam arms 83 and 84 for engagement with the segments 101 secured to the main frame 1 for locking the cutters in contact with the work.

The mode of operation of the improved rock cutting machine will be described as follows: Assuming that the disk-shape cutter supporting beams 58 and 59 are in their open position and that the rock supporting table 12 and the rock clamping table 30 are also spaced apart as far as possible. A rock (not shown) to be cut is placed on the feed roller 25 and rolled onto the rock supporting table 12. The handle 45 is firmly grasped and pulled down, thereby causing the cams 37 and 38, and the cams 51 and 52 to force the rock clamping table 30 down onto the rock to firmly clamp the rock in fixed position. The pivoted pawls 41 and 42 will lock the table 30 in fixed position. After this, the oil under pressure is let into the hydraulic cylinder 82 through the tubing 99

75

to force the upper and lower disk-cutter supporting beams together until the cutters 66 are firmly engaged with the upper and lower surfaces of the rock to be cut. The shaft 16' is then rotated to operate the pitmans 19 and 20 to reciprocate the tables 12 and 30 with the rock supported therebetween back and forth. As the rock is cut, additional oil under pressure is fed to the hydraulic cylinder 82, and the beams 58 and 59 are locked in adjusted position by means of the pawls 100, engaging the segments 101.

From the foregoing description, it will be apparent that a highly efficient rock cutting machine has been devised and provided.

While the preferred embodiment of the instant invention has been illustrated and described, it will be understood that it is not intended to limit the scope of the invention thereto, as many minor changes in details of construction may be resorted to without departure from the spirit of the invention.

Having described the invention what is claimed as new is:

1. A rock cutting machine comprising a stationary frame, a rock-supporting table reciprocably mounted thereon, supporting and thrust bearing wheels for said table, a rock-clamping table disposed above said rock supporting table and movable therewith, vertically movable cutter supporting beams disposed above and below said tables, rotatable disk-shaped cutters on said beams, resilient supporting means both for the upper cutter supporting beam and for said rock-clamping table, manually actuated cams for adjusting said rock clamping table towards said rock supporting table, and hydraulic operated cam means for moving said cutter supporting beams towards each other.

2. A rock cutting machine comprising a stationary frame, a rock-supporting table reciprocably mounted thereon, supporting and thrust bearing wheels for said table, a rock-clamping table disposed above said rock supporting table and movable therewith, vertically movable cutter supporting beams disposed above and below said tables, rotatable disk-shaped cutters on said beams, resilient supporting means both for the upper cutter supporting beam and for said rock-clamping table, manually actuated cams for adjusting said rock clamping table towards said rock supporting table, hydraulic operated cam means for moving said cutter supporting beams towards each other, and pivoted locking pawls for holding said cutter supporting beams in the desired adjusted position.

3. A rock cutting machine comprising a stationary frame, a rock-supporting table reciprocably mounted thereon, supporting and thrust bearing wheels for said table, a rock-clamping table disposed above said rock supporting table and movable therewith, vertically movable cutter supporting beams disposed above and below said tables, rotatable disk-shaped cutters on said beams, resilient supporting means both for the upper cutter supporting beam and for said rock-clamping table, manually actuated cams for adjusting said rock clamping table towards said rock supporting table, hydraulic operated cam means for moving said cutter supporting beams towards each other, vertically adjustable brackets for supporting said beams in the desired adjustment with respect to said frame, and pivoted locking pawls for holding said cutter supporting beams in their clamped position.

4. A rock cutting machine comprising a stationary frame, a rock supporting table reciprocably mounted thereon, a guide roller secured to said frame, a rock clamping table secured above said rock supporting table and movable therewith, shafts mounted in said rock clamping table, cam members on said shafts and engaging said rock clamping table, stop means engaging one of said cam members, a lever secured to one of said shafts for lowering the rock clamping table into operative position, vertically slidable cutter supporting beams disposed above and below said tables, and rotatable disk-shaped cutters on said beams.
5. The combination of claim 4, wherein said rock clamping table includes a plurality of U-shaped channel members and a length of rubber hose secured in each of the inverted U-shaped channel members below the lower extremity thereof for providing non-slip engagement with a rock.
6. A rock cutting machine comprising a stationary frame, a rock supporting table reciprocably mounted thereon, a guide roller secured to said frame, a rock clamping table secured above said rock supporting table and movable therewith, shafts mounted in said rock clamping table, cams on said shafts and engaging said rock clamping table, stop means engaging one of said cams, a lever secured to one of said shafts for lowering the rock clamping table into operative position, vertically slidable cutter supporting beams disposed above and below said tables, rotatable disk-shaped cutters on said beams, cam means secured to the upper cutter supporting beam, and hydraulic means operating said last-named cam means to move the cutter supporting beams towards each other.
7. The combination of claim 6, wherein said hydraulic means is a piston and cylinder, link means securing said hydraulic means and said cam means for operative engagement, and bearing rollers on said cam means engaging the ends of said beams for forcing them together.
8. The combination of claim 7, and pivoted locking pawls secured to said machine for holding said cutter supporting beams in the desired adjusted position.
9. A rock cutting machine comprising a stationary frame, a rock-supporting table reciprocably mounted on said frame, a guide roller secured to said frame, a rock clamping member secured above said rock-supporting table and movable therewith, shafts carried by said rock-clamping member, cams on said shafts and engaging said rock-clamping member, a lever secured to one of said shafts for lowering the rock-clamping member into operative position, vertically slidable cutter supporting beams disposed above and below said rock-supporting table and said rock-clamping member, and rotatable cutters on said beams.

EDWARD SWIFT.
